CARBURETOR ATTACHMENT

Roger W. Stadman, Los Angeles, Calif.

Application February 25, 1935, Serial No. 8,035

4 Claims. (Cl. 123—119)

This invention relates to carburetion and more particularly to forming a combustible mixture for an internal combustion engine; and has for its object to properly proportion and mix the air and fuel under varying conditions of load and speed.

More particularly it is an object of the invention to increase the jet action at the fuel nozzle of the carburetor which forms the combustible mixture, so as to generate a dry gas, and preferably to increase the jet action as the throttle is opened.

It is a further object of the invention to increase the pressure of the air which at the Venturi tube of the carburetor entrains and then atomizes and vaporizes the fuel, and to preferably increase the air pressure as the throttle is opened.

Further objects of the invention will be readily understood from the following description of the accompanying drawing, in which:

Fig. 1 is a side elevation of the invention, with the throttle in idling position.

Fig. 2 is a transverse section on the line 2—2 of Fig. 1, with the throttle in full open position.

Fig. 3 is an axial section on the line 3—3 of Fig. 2.

The invention is applicable to a usual carburetor for an internal combustion engine, the carburetor including fuel nozzle 1 supplied from a float chamber 2 and having an air intake 3 from whence the air flows through a Venturi tube 4 which surrounds the fuel nozzle. As shown at Fig. 1 the fuel nozzle preferably opens into the Venturi tube in the direction of flow through the Venturi tube, and the discharge orifice of the fuel nozzle is preferably at or adjacent the maximum cross-sectional restriction of the Venturi tube. A combustible mixture is thus formed in usual manner and is drawn through the intake manifold 5 and past the throttle valve 6 into the engine cylinders, the exhaust manifold for the engine cylinders being shown at 7.

The present invention preferably provides additional flow into the intake manifold 5 as the throttle 6 is opened; and this additional flow is under considerable pressure and creates turbulence in the intake manifold as well as reducing the vacuum therein, and is preferably also adapted to raise the temperature of the combustible mixture and to supply exhaust gases thereto.

For this purpose a housing 10 may be mounted in the intake manifold 5, preferably between its usual coupling flanges 11—12, the housing being held in place by the usual flange bolts 13. The

housing has a bore 14 in alignment with and slightly larger than the bore of the intake manifold, and a sleeve 15 is mounted in this bore and is held in place between the flanges 11—12 as shown at Fig. 3. The sleeve 15 has a series of circumferentially spaced ports 16 opening into the bore of the intake manifold, and the housing 10 forms an annular chamber 17 surrounding and communicating with the ports, with a passageway 18 leading to the annular chamber. 10

At its outer end the passageway 18 communicates with a valve chamber 19 which is formed in housing 10, the valve chamber being shown as cylindrical and adapted to receive a rotary valve 20, and the valve chamber has an intake 15 nipple 21 circumferentially spaced from the passageway 18. The valve 20 when turned to the position shown at Fig. 1 closes the intake nipple 21, but is cut away at one side as shown at 22 so that when turned in the direction of arrow A to the position shown at Figs. 2 and 3, it opens the nipple 21 to the passageway 18. 20

The valve 20 may be rotated by a lever 23 which is linked at 24 to the lever 25 for the throttle valve 6, so that when throttle rod 27 is shifted 25 in the direction to open the throttle 6, the valve 20 is also opened as shown at Fig. 3, and when the throttle is closed to idling position the valve 20 is also closed as shown at Fig. 1.

Exhaust gases from the engine are preferably 30 supplied to the intake nipple 21, and for this purpose a conduit 30 communicates with the exhaust manifold 7 and leads to the intake nipple.

The invention provides means for increasing the jet action at fuel nozzle 1, preferably as the 35 throttle 6 is opened, and for this purpose additional flow under pressure is supplied to the mouth of the Venturi tube 4 for entraining and then atomizing and vaporizing fuel, and this additional flow is preferably adapted to raise the 40 temperature of the fuel which is drawn into the Venturi tube and to supply exhaust gases thereto.

For this purpose a conduit 35 has a discharge end 36 surrounding the fuel nozzle 1 in the mouth of Venturi tube 4, with the discharge end 36 preferably at or adjacent the discharge orifice of the fuel nozzle as shown at Fig. 1, whereby the discharge end 36 is preferably at or adjacent the maximum cross-sectional restriction of the Venturi tube. The conduit 35 is preferably supplied 50 with exhaust gases from the manifold 7, the supply being preferably controlled in accordance with the position of the throttle 6. As an instance of this arrangement the valve chamber 10 may have an outlet nipple 37 communicating 55

with the conduit 35, and the cut away portion of valve 20 may be so arranged that when the valve is turned for opening the intake nipple 21 to the passageway 18, it also opens the intake nipple to the outlet nipple 37 as shown at Fig. 3.

In operation, when the throttle 6 is closed to idling position the valve 20 is also closed, so that the carburetor supplies a combustible mixture in usual manner, with suction past the nearly completely closed throttle drawing in air through intake 3 so that the air entrains and then atomizes and vaporizes fuel at the point of maximum cross-sectional restriction of the Venturi tube 4, but as the throttle 6 is opened the valve 20 is correspondingly opened, whereby exhaust gases are supplied via conduit 35 for discharge into the stream of air being drawn in through the air intake 3, with said discharge adjacent the orifice of the fuel nozzle and adjacent the point of maximum cross-sectional restriction of the Venturi tube 4. The exhaust gases thus function with maximum efficiency to increase the jet action of the stream of air for drawing fuel into the Venturi tube, thereby maintaining the proper fuel ratio for different speeds and loads and heating the fuel for complete vaporization, and by forming a part of the combustible mixture insuring fuel economy and tending to maintain the same proportion of exhaust gases in the fuel charge at different positions of the throttle.

At the same time a part of the exhaust gases, controlled by the position of valve 20 which is in turn controlled by the position of the throttle, are preferably discharged through ports 16 into the combustible mixture in the intake manifold 5, the additional flow being introduced at a point between the throttle valve 6 and the cylinders of the engine as shown at Fig. 1. These exhaust gases being under pressure reduce the vacuum in the intake manifold as the engine is accelerated, thereby assisting in maintaining the proper fuel ratio for different speeds and loads, and also create turbulence in the intake manifold, insuring a thorough mixture of the air and fuel.

The invention thus provides an efficient combustible mixture with the air and fuel properly proportioned for varying conditions of speed and load, and with the exhaust gases which are supplied to the Venturi tube at its maximum cross-sectional restriction and at the discharge orifice of the fuel nozzle, thereby functioning with maximum efficiency to increase the jet action and supply heat for vaporizing the fuel, thus supercharging the combustible mixture and increasing the volumetric efficiency of the engine, making it possible to burn low grade fuel oils in a low compression, high speed engine.

I claim:

1. In a carburetor adapted to form a combustible mixture for an internal combustion engine, a Venturi tube having an air inlet at one end and at its opposite end forming a passageway supplying combustible mixture to the engine,

a fuel jet having a discharge orifice opening into the Venturi tube in the direction of flow therethrough and at a point just before maximum restriction of the Venturi tube, a conduit for exhaust gases of the internal combustion engine 5 having a discharge end surrounding the fuel jet and opening into the Venturi tube at the discharge orifice of the jet, a valve controlling flow of exhaust gases through said conduit, a throttle controlling flow of combustible mixture to the engine, and means for opening and closing the valve in accordance with opening and closing of the throttle.

2. In a carburetor adapted to form a combustible mixture for an internal combustion engine, 15 a Venturi tube having an air inlet at one end and at its opposite end forming a passageway supplying combustible mixture to the engine, a fuel jet having a discharge orifice opening into the Venturi tube in the direction of flow therethrough and at a point just before maximum restriction of the Venturi tube, a conduit for fluid which will mix with and form a component of the combustible mixture, said conduit having a discharge end surrounding the fuel jet and opening 20 into the Venturi tube adjacent the discharge orifice of the jet, a valve controlling flow of fluid through the conduit, a throttle controlling flow of combustible mixture to the engine, and means for opening and closing the valve in accordance 25 with the position of the throttle.

3. In a carburetor adapted to form a combustible mixture for an internal combustion engine, 35 a Venturi tube having an air inlet at one end and at its opposite end forming a passageway supplying combustible mixture to the engine, a fuel jet having a discharge orifice opening into the Venturi tube adjacent maximum restriction of the Venturi tube, a conduit for exhaust gases of the internal combustion engine having a discharge end opening into the Venturi tube just before maximum restriction of said tube, a valve controlling flow of exhaust gases through said conduit, a throttle controlling flow of combustible mixture to the engine, and means for opening 40 and closing the valve in accordance with the position of the throttle.

4. In a carburetor adapted to form a combustible mixture for an internal combustion engine, 45 a Venturi tube having an air inlet at one end and at its opposite end forming a passageway supplying combustible mixture to the engine, a fuel jet having a discharge orifice opening into the Venturi tube adjacent maximum restriction of the Venturi tube, a conduit for fluid which will mix with and form a component of the combustible mixture, said conduit having a discharge end opening into the Venturi tube adjacent the discharge orifice of the jet, a valve controlling flow of fluid through the conduit, a throttle controlling flow of combustible mixture to the engine, and means for opening and closing the valve in accordance with the position of the throttle.

ROGER W. STADLMAN.
